UNITED STATES PATENT OFFICE.

MORTON L. JOHNSON, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONY.

1,075,258.

Specification of Letters Patent.

Patented Oct. 7, 1913.

Application filed December 4, 1912. Serial No. 734,865.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to those telephone exchange systems including telephone lines extending from subscribers' stations to an exchange at some of which stations are located devices requiring operation by calling subscribers after responses by called subscribers in order to complete connection between calling and called subscribers, there being means at the subscribers' stations co-operating with these devices and operable by responding called subscribers, link connectors at the exchange for uniting lines in conversation, switching mechanism for breaking telephonic connection between calling and called stations for telephonic current impressed upon calling lines at calling stations, electro-magnetic mechanism governed by the aforesaid devices at calling stations equipped therewith in co-operation with the aforesaid means at stations of responding called subscribers for operating said switching mechanism to complete connection between calling and called stations, and means for completing telephonic connection between calling and called stations for telephonic current impressed upon called lines at called stations when telephonic connection is broken between calling and called stations for current impressed upon calling lines at calling stations.

In my co-pending application Serial No. 734,864 filed December 4, 1912 I have illustrated operator controlled means for enabling the completion of connections between calling and called stations so as not to require operation by calling subscribers of the devices located at stations employed for the purpose of charging calling subscribers with connections.

In my present invention I employ means whereby calling subscribers may signal an operator whose function it is to pass upon the propriety of permitting such calling subscriber to have free connection.

In the preferred embodiment of the inven-

tion link connectors are employed which the calling subscribers are enabled to use for establishing connection between calling and called stations and which are provided with equipment, controlled by calling and called stations, for the purpose of preventing complete connections between calling and called stations until after the calling party has operated the device at his station that will charge such calling party with the connection to be effected. This equipment is supplemented by means also governed by the calling subscriber whereby his line may be automatically extended into connection with the operator provided for the purpose stated.

I will explain my invention more fully by reference to the accompanying drawings in which—

Figures 1, 2 and 3, taken collectively, with the conductors terminating at the right hand end of Fig. 1 in alinement with the conductors terminating at the left hand side of Fig. 2 and the conductors terminating at the right hand side of Fig. 2 in alinement with the conductors terminating at the left hand side of Fig. 3, illustrate the preferred form of telephone exchange system employing automatic means for extending calling lines, the particular system illustrated being one in which the extensions applied to calling lines are also automatically connected with called lines, though the invention is not to be limited to systems employing this latter step.

The prepayment of precharge station A, of which there are of course a number, and the called station B, which may or may not be a prepayment or precharge station, are illustrated as being each provided with the usual telephone equipment including a telephone receiver switch hook 1 having a normal contact for connecting the line sides through a signal bell 2 and a condenser 3 when the telephone receiver 4 is upon its switch hook. The switch hook has an alternate contact whereby the telephone receiver 4 and telephone transmitter 5 are included across the line sides when the telephone receiver is removed from its switch hook. Assuming that the party at station A is initiating a call, the receiver 4 at the calling station A is free of its switch hook to permit said switch hook metallically to connect the sides of the calling line whereby circuit is

established through the selector switch line relay 6 by circuit connections which are apparent. Calling subscriber, after having removed his telephone receiver from its 5 switch hook, operates his dial mechanism, which is illustrated in diagrammatic form, by the normally closed circuit interrupting switch 7 whereby a circuit of the magnet 6 is intermittently opened for the purpose of 10 causing its armature switch to be vibrated at a predetermined rate of speed. When this armature switch is attracted it establishes a circuit through the sluggishly operating relay 8. When the armature of relay 6 drops 15 back (the armature of relay 8 still being up, owing to the sluggishness of this relay) a circuit is established traceable from the grounded armature switch of relay 6 through its normal contact, the lower armature 20 switch of relay 8 and its alternate contact, the vertical magnet 9, the sluggishly operating relay 10, the side switch wiper 11 in its normal position, to the grounded battery 12. The vertical magnet raises the wipers 13, 14 and 15 to the level of a bank of waiting contacts that includes waiting contacts pertaining to a desired link connector which 25 is to be automatically connected with the calling line for the purpose of extending the calling line into connection with a called line. When the desired level of waiting contacts has been attained, the circuit of the private magnet 16, which was closed upon the energization of relay 10 at the armature 30 switch of this relay, is opened due to the maintained attraction of the armature switch of relay 6, and the circuit of the vertical magnet 9 is also opened at said armature switch of relay 6. The vertical 35 magnet 9 therefore ceases to elevate the wipers 13, 14, 15 while the private magnet 16 serves to step the side switch wipers 11 and 17 to their second positions. When the side switch wiper 11 is put in its second position 40 circuit for the rotary magnet 18 is closed through the interrupter 19 whereby the wipers 13, 14 and 15 are stepped around until the wiper 14 engages an ungrounded contact. When this ungrounded contact is 45 encountered circuit for the private magnet 16, which was again closed upon the initial operation of the rotary magnet 18, is opened whereby the side switch wipers 11 and 17 are moved to their final position, the side 50 switch wiper 11 in being moved to this final position opening the circuit of the rotary magnet 18 whereby the wipers 13, 14 and 15 are brought to rest with the wipers 13 and 15 in connection with the talking sides of 55 the automatically selected link connector that is to constitute the extension of the calling line.

It is understood that there are a plurality of the link selector switches being described 60 for a group of telephone lines and that the

wipers of these switches are provided with waiting contacts that are individual to the link connectors, each link connector having waiting contacts in the different switches and which are similarly positioned, the similarly positioned waiting contacts being in multiple connection. When the wiper 17 has been brought to its final position it connects the wiper 14 with ground by way of the upper armature switch of the sluggishly operating relay 8, this ground being substituted for another ground which will later appear. In this way the contact engaged by the actuated wiper 14 is grounded and similarly positioned contacts in other switches of the same group are also grounded owing to their multiple relation with the aforesaid waiting contact so that other switches cannot select the link connector selected by the switch under description. When the side switch wiper 11 is in its third position a circuit is established for the switching relay 20 which may be traced from the grounded battery 12, the wiper 11 in its final position, the relay 20, 70 the upper armature switch of relay 8 and its contact to ground, this ground later being replaced by another ground as will later appear. The relay 20, now being energized, connects the wipers 13 and 15 with the sides 75 of the calling line so that these calling line sides are extended into connection with the talking sides of the selected link connector. At the right hand end of Fig. 1 the wipers 13, 14 and 15 are indicated in dotted lines. These are the same wipers which are shown in full lines just to the left and are thus 80 illustrated for the purpose of showing these wipers in another level. The level illustrated in connection with the wipers 13, 14 and 15 where shown by dotted lines is one of a number of levels that are used in ordinary automatic or semi-automatic practice. The level shown in connection with the wipers 13, 14 and 15 is an especially 85 provided level for one of the purposes of the invention and is employed to enable calling subscribers to become connected with called subscribers without having to operate any prepayment or precharge device. 90

It will be first assumed that the calling subscriber is not making an emergency call but desires to secure connection with a called subscriber as usual. In such event the wipers 13, 14 and 15 will be brought to some 95 level in which are provided waiting contacts that, in the embodiment of the invention illustrated, constitute terminals of an idle link connector extending to a connector switch illustrated at C, under the assumption that the system is an automatic system, the connector switch C being operated 100 by the calling subscriber's circuit interrupter 7 in the establishment of connection between calling and called subscribers for bringing 105 110 115 120 125 130

the wipers of the connector switch into association with the called line, this operation being accomplished in the usual manner, and as the connector switch is a device which is well known by those skilled in the art a description thereof will not be furnished but reference may be had to British Patent 1298 of 1910 and to Van Deventer's *Telephonology*, page 530, for an understanding of such connector switches.

When the wipers 13, 14 and 15 have been brought to rest a circuit is established which is traceable from the grounded battery 12, the upper winding of the relay 21, the upper 15 20 and its alternate contact, the upper armature switch of relay 23 and its normal contact, the circuit interrupter 7 at the calling stations, the telephone bridge at the calling station, the lower 20 25 armature switch of relay 23 and its normal contact, the intermediate armature switch of relay 20 and its alternate contact, the wiper 15 and the contact engaged thereby, the lower winding of differential magnet 22, the lower winding of magnet 21, to ground. The cumulatively wound relay 21 now attracts its armature switches, the upper armature switch of this relay closing circuit for the sluggishly operating relay 24 whereby the uppermost armature switch of the sluggishly operating relay places ground upon the contact engaged by the wiper 14 in lieu of the ground now removed at the upper armature switch of sluggishly operating relay 8 consequent upon the operation of the relay 20. The lower armature switch of relay 21 establishes a bridge connection between the talking sides of the link connector extending to the connector switch C, which bridge connection may be traced from the lower talking side of the link connector, the lower armature switch of relay 21 and its engaged contact, the polarized relay 25, to the upper talking side of such link connector. This bridge connection closes circuit for the well known line relay 26 belonging to the connector switch C, as will be apparent. When the connection is initially established the direction of current from the common 50 55 battery 12 is such that the armature of the polarized relay 25 will remain in the position shown in Fig. 2 until the called subscriber responds whereupon the connection of the battery 12 in its circuit with the polarized relay 25 will be reversed to cause the armature of the relay 25 to engage its contact for the purposes to be stated. A sluggishly operating relay 27 remains energized during the operation of the calling subscriber's interrupter 7, the circuit for the relay 27 being traceable from the grounded battery 12, the winding of the relay 27, the lower armature switch of relay 26 and its contact, the upper armature switch of relay 21 and its 60 65 normal contact, to ground. The circuit in-

terruptions occasioned by the calling subscriber's interrupter 7 are effective in opening and closing the circuit of the line relay 26 of the connector switch C at the lower armature switch of relay 21, this relay 21 70 being intermittently energized and deenergized consequent upon the operation of the interrupter 7. During these impulses the bridge containing the polarized relay 25 (which may be a resistance of five hundred ohms) is shunted by the low resistance bridge traceable from the upper armature switch of relay 27 and its alternate contact, the lower armature switch of relay 21 and its engaged contact, to the lower armature switch of relay 27 to bring the relay 26 into control of the interrupter 27. The wipers of the connector switch are consequently located in the proper level and are moved about until they engage waiting contacts of the called line, all as will be well understood by those skilled in the art. When the called subscriber responds the back bridge relay 28 of the connector switch C is included in circuit, the two upper armature switches of this back bridge relay engaging their alternate contacts to reverse the connection of the battery 12 in its circuit with the relay 25 to cause the armature switch of this relay 25 to be shifted. When 95 this switch is shifted circuit for the relay 29 is established from the grounded battery 12 through this relay 29, the armature switch of the polarized relay 25 and its then engaged contact, the lower armature switch of relay 30 to its grounded contact. The upper armature switches of relay 29 are provided with connected normal contacts and the lower armature switches of this relay are also provided with connected normal contacts.

The top and bottom armature switches are connected with the portion of the selected link connector extending to the connector switch C and the intermediate armature switches are connected with the portions of the link connector extending to the waiting contacts engaged by the wipers 13 and 15 of the link selector switch. Thus when the relay 29 is deenergized the link connector intervening between the link selector switch and the connector switch is telephonically completed excepting for the gap established at the relay 27 during the impulses employed for operating the connector switch C. When the relay 29 is energized the connections between its armature switches established by their normal contacts are broken so that at these points telephonic connection between the calling and called lines is open. The alternate contacts of the intermediate armature switches of relay 29 are connected through an induction coil 31 whereby this induction coil is serially connected with the calling line. This induction 125 130

coil 31 is in inductive relation with a primary 32 included in a local circuit that contains a telephone transmitter 33. The transmitter 33 is to be operated by a telephone receiver 34 which is included in a conductor that terminates in the alternate contacts of the top and bottom armature switches of relay 29 whereby this receiver 34 is connected with the called subscriber 5 when the relay 29 is energized. A secondary 35 is included in series with the receiver 34, this secondary having a primary 36 that is included in a local circuit with a transmitter 37 into which a talking device 38 10 speaks. This talking device may be in the nature of a phonograph and the record of the phonograph may be suited to the purpose of the system. For example, the phonograph may speak "What is your number?—Register please", sufficient time intervening between the reproductions of these phrases within which the called subscriber may give his number and the calling subscriber may deposit his coin 39. Both 15 subscribers hear these phrases as will be apparent. The announcement of the number made by the called party will be relayed from the receiver 34 to the transmitter 33 and from the induction coil 32 to the induction coil 31 whereby the calling party will hear the number announced by the called party. Any current impressed upon the line at the calling station will not however be relayed to the called station since the transmitter 33 is incapable of relaying these voice 20 currents impressed at the calling station by way of the receiver 34. When the calling subscriber hears the phrases automatically announced by the phonograph he 25 knows that a called subscriber has answered and when he hears the called subscriber's number the calling subscriber will know that the proper party has answered and will thereupon deposit the coin 39. When the coin 39 is deposited a circuit is momentarily established which is traceable from the grounded contact of the switch 40, the companion contact of this switch, the switch hook 1, thence by connections which are apparent to the wiper 15 and from this wiper 15 by connections which are apparent to the lower coil of the differential relay 22, to the grounded coil of the cumulatively wound relay 21. By connections which are equally 30 obvious the switch 40 is also included in circuit with the upper winding of the differential relay 22. The coils of the relay 22 are thus thrown out of balance so that this relay is energized to attract its armature 35 switch to complete the circuit of the relay 30 traceable from the grounded battery 12 the winding of relay 30, the lower armature switch of differential relay 22, the now attracted armature switch of relay 41 (which 40 is energized consequent upon the closure of the switch of the polarized relay 25) to ground. The relay 30 establishes a locking circuit for itself traceable from the battery 12, its upper armature switch and its engaged contact to the upper grounded armature switch of relay 24. When the relay 30 is energized circuit for the relay 29 is opened at the lower armature switch of relay 30 so that the armature switches of the relay 29 are restored to normal whereby connection 45 is completed between the calling and called lines so that the parties at the calling and called stations may each talk with the other. When the subscribers are through conversation they will restore their receivers upon their switch hooks, in which event the connector switch will be restored to normal in a manner well understood by those skilled in the art, and the link selector switch will be restored to normal in a manner well known by those familiar with automatic telephone practice. 50 Assuming that the calling subscriber has an emergency or special call, say for a doctor or for a fire alarm station and has no coin to operate his switch 40, or in case the calling subscriber wishes to use the telephone service for the company's business, such calling subscriber will, by suitable manipulation of his interrupter 7, select the 55 level illustrated in association with the wipers 13, 14 and 15 as shown in full lines in Fig. 1. Such a level of waiting contacts has contact buttons which constitute terminals of link connectors that extend to selector switches such as illustrated at D (which may be of the usual type of selector switches as employed in pure automatic practice and which need not therefore be described in detail) and which are employed 60 for extending the calling line into connection with an idle operator's position, this operator's position corresponding to the called station B which was previously described as being connected with the calling line by the connector switch C. The wipers of the selected selector switch D travel until the wiper 42 engages an ungrounded waiting contact, such contact being ungrounded when the corresponding operator is idle. 65 When the wipers 43 and 44 rest upon corresponding waiting contacts, the relay 45 is placed in bridge of the calling line and is consequently energized. The upper and grounded armature switch of the relay 45 places ground upon the button engaged by the wiper 42 so that any such wiper of any other selector switch D will not remain in engagement with a similarly positioned contact button in multiple connection with the button thus grounded whereby the same operator is guarded from selection by more than one selector switch. The lower armature switch of the relay 45, when attracted, establishes a circuit through the signal de- 70 75 80 85 90 95 100 105 110 115 120 125 130

vice 46 to attract the attention of the idle operator who depresses her listening key 47 to bring her telephone set 48 into circuit relation with the calling subscriber. If the 5 operator ascertains that the calling subscriber is entitled to free use of a telephone connection such operator will effect or permit the extension of the calling line into connection with the line of the station 10 desired by the calling subscriber.

In the embodiment of the invention illustrated the various lines are provided with spring jacks 49 located before such operator and the link connector conductors that enable the operators to effect connection between their telephones and the telephones of calling subscribers are extended into connection with terminal plugs 50 which may be inserted within jacks 49 for the purpose 15 of completing connection between calling 20 and called subscribers. The link connector terminating in the plug 50 may be provided with the usual supervisory apparatus which need not be described and may be provided 25 with the usual ringing outfit for signaling the called subscriber's bell, all as is well understood by those skilled in the art.

The operator may, from time to time, bridge her telephone into the established circuit to make sure that the calling subscriber 30 is using the established circuit properly within his privilege.

I believe it to be broadly new with me to provide a system of the class indicated 35 in which there is provided a special operator's position for "franking" connections between calling and called stations whether prepaid or precharge connections are established with the aid of the automatic equipment illustrated or by any other means, 40 semi-automatic or manual.

While I have herein shown and particularly described the preferred embodiment of my invention, I do not wish to be limited to 45 the precise details of construction and circuit arrangement shown as changes may readily be made without departing from the spirit of the invention, but

Thus having described my invention, I 50 claim as new and desire to secure by Letters Patent the following:—

1. A telephone exchange system including telephone lines extending from subscribers' stations to an exchange at some of which 55 stations are located devices requiring operation by calling subscribers after responses by called subscribers in order to complete connection between calling and called subscribers, there being means at the subscribers' 60 stations coöperating with these devices and operable by responding called subscribers; link connectors at the exchange for uniting lines in conversation; switching mechanism associated with said link connectors for 65 breaking telephonic connection between call-

ing and called stations for telephonic current impressed upon calling lines at calling stations; electro-magnetic mechanism governed by the aforesaid devices at calling stations equipped therewith in coöperation with the 70 aforesaid means at stations of responding called subscribers for operating said switching mechanism and completing connection between calling and called stations; additional operator controlled link connectors 75 for establishing connection between calling and called stations independently of the devices requiring operation by calling subscribers after responses by called subscribers; means whereby calling subscribers may 80 have telephonic connection with an operator independently of his device requiring operation in precharged or prepaid connections; and electro-magnetic switching mechanism for automatically connecting the additional 85 link connectors with calling lines.

2. A telephone exchange system including telephone lines extending from subscribers' stations to an exchange at some of which 90 stations are located devices requiring operation by calling subscribers in order to complete connection between calling and called subscribers; link connectors at the exchange for uniting lines in conversation; switching mechanism associated with said 95 link connectors for breaking telephonic connection between calling and called stations for telephonic current impressed upon calling lines at calling stations; electro-magnetic mechanism operated by the aforesaid 100 devices at calling stations equipped therewith for operating the switching mechanism to complete connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or 105 prepaid connections; and electro-magnetic switching mechanism for automatically connecting the additional link connectors with 110 calling lines.

3. A telephone exchange system including telephone lines extending from subscribers' stations to an exchange at some of which 115 stations are located devices requiring operation by calling subscribers after responses by called subscribers in order to complete connection between calling and called subscribers, there being means at the subscribers' 120 stations coöperating with these devices and operable by responding called subscribers; link connectors at the exchange for uniting lines in conversation; switching mechanism associated with said link connectors for breaking 125 telephonic connection between calling 130

- 6 and called stations for telephonic current impressed upon calling lines at calling stations; electro-magnetic mechanism governed by the aforesaid devices at calling stations 5 equipped therewith in coöperation with the aforesaid means at stations of responding called subscribers for operating said switching mechanism and completing connection between calling and called stations; additional operator controlled link connectors 10 for establishing connection between calling and called stations independently of the devices requiring operation by calling subscribers after responses by called subscribers; means whereby calling subscribers may have telephonic connection with an operator independently of his device requiring operation in precharged or prepaid connections; means whereby the operator may supervise 15 uncharged connections between calling and called stations; and electro-magnetic switching mechanism for automatically connecting the additional link connectors with calling lines.
- 20 25 4. A telephone exchange system including telephone lines extending from subscribers' stations to an exchange at some of which stations are located devices requiring operation by calling subscribers in order to complete connection between calling and called subscribers; link connectors at the exchange for uniting lines in conversation; switching mechanism associated with said link connectors for breaking telephonic connection between calling and called stations for telephonic current impressed upon calling lines at calling stations; electro-magnetic mechanism operated by the aforesaid devices at calling stations equipped there- 30 35 40 45 50 55 60 65 70 75 80 85 90 95 100 105 110 115 120 125 130 with for operating the switching mechanism to complete connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or prepaid connections; means whereby the operator may supervise uncharged connections between calling and called stations; and electro-magnetic switching mechanism for automatically connecting the additional link connectors with calling lines.
5. A telephone exchange system including telephone lines extending from subscribers' stations to an exchange at some of which stations are located devices requiring operation by calling subscribers after responses by called subscribers in order to complete connection between calling and called sub- 65 70 75 80 85 90 95 100 105 110 115 120 125 130
- stations coöperating with these devices and operable by responding called subscribers; link connectors at the exchange for uniting lines in conversation; switching mechanism associated with said link connectors for breaking telephonic connection between calling and called stations for telephonic current impressed upon calling lines at calling stations; electro-magnetic mechanism governed by the aforesaid devices at calling stations equipped therewith in coöperation with the aforesaid means at stations of responding called subscribers for operating said switching mechanism and completing connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or prepaid connections; and electro-magnetic switching mechanism for automatically connecting the aforesaid link connectors with calling lines.
6. A telephone exchange system including telephone lines extending from subscribers' stations to an exchange at some of which stations are located devices requiring operation by calling subscribers in order to complete connection between calling and called subscribers; link connectors at the exchange for uniting lines in conversation; switching mechanism associated with said link connectors for breaking telephonic connection between calling and called stations for telephonic current impressed upon calling lines at calling stations; electro-magnetic mechanism operated by the aforesaid devices at calling stations equipped therewith for operating the switching mechanism to complete connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or prepaid connections; and electro-magnetic switching mechanism for automatically connecting the aforesaid link connectors with calling lines.
7. A telephone exchange system including telephone lines extending from subscribers' stations to an exchange at some of which stations are located devices requiring operation by calling subscribers after responses by called subscribers in order to complete connection between calling and called sub-

scribers, there being means at the subscribers' stations coöperating with these devices and operable by responding called subscribers; link connectors at the exchange for uniting lines in conversation; switching mechanism associated with said link connectors for breaking telephonic connection between calling and called stations for telephonic current impressed upon calling lines at calling stations; electro-magnetic mechanism governed by the aforesaid devices at calling stations equipped therewith in cooperation with the aforesaid means at stations of responding called subscribers for operating said switching mechanism and completing connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or prepaid connections; means whereby the operator may supervise uncharged connections between calling and called stations; and electro-magnetic switching mechanism for automatically connecting the aforesaid link connectors with calling lines.

8. A telephone exchange system including telephone lines extending from subscribers' stations to an exchange at some of which stations are located devices requiring operation by calling subscribers in order

to complete connection between calling and called subscribers; link connectors at the exchange for uniting lines in conversation; switching mechanism associated with said link connectors for breaking telephonic connection between calling and called stations for telephonic current impressed upon calling lines at calling stations; electro-magnetic mechanism operated by the aforesaid devices at calling stations equipped therewith for operating the switching mechanism to complete connection between calling and called stations; additional operator controlled link connectors for establishing connection between calling and called stations independently of the devices requiring operation by calling subscribers after responses by called subscribers; means whereby calling subscribers may have telephonic connection with an operator independently of his device requiring operation in precharged or prepaid connections; means whereby the operator may supervise uncharged connections between calling and called stations; and electro-magnetic switching mechanism for automatically connecting the aforesaid link connectors with calling lines.

In witness whereof, I hereunto subscribe my name this twenty-seventh day of November A. D., 1912.

MORTON L. JOHNSON.
